UNITED STATES PATENT OFFICE.

CHARLES L. BASTIAN, OF CHICAGO, ILLINOIS, ASSIGNOR, BY MESNE ASSIGNMENTS, TO
BOTTLERS MACHINERY MANUFACTURING COMPANY, OF CHICAGO, ILLINOIS, A
CORPORATION OF ILLINOIS.

BOTTLE-FILLING MACHINE.

1,000,971.

Specification of Letters Patent. Patented Aug. 15, 1911.

Application filed February 13, 1905. Serial No. 245,522.

To all whom it may concern:

Be it known that I, CHARLES L. BASTIAN, a citizen of the United States, residing at Chicago, in the county of Cook and State 5 of Illinois, have invented certain new and useful Improvements in Bottle-Filling Machines, of which the following is a specification.

My invention relates to bottle filling machines, and is designed primarily to serve 10 as a counter-pressure filling machine, although capable, by the omission of certain parts, to serve as a direct gravity filling machine; the machine of the invention being 15 capable of handling all fluids, whether thick or thin and whether still or under pressure.

The machine is of that general type employing a rotary tank head from which are suspended an annular series of valves adapted 20 for coöperation with the bottles raised thereto and retracted therefrom by a series of rotatable and vertically movable bottle holders carried by the main rotary stem or upright of the machine.

My invention has for its principal objects 25 to provide a machine of this character which shall be capable of much greater speed than machines of this class now in use; which shall be capable of handling bottles of widely 30 varying kinds; which shall treat the bottles with a minimum of jar and shock, thus reducing the liability of foaming and breakage; to produce a machine in which the liquid discharged in the snifting operation 35 is preserved, thus conducing to economy; and generally to provide an improved and highly efficient filling machine having a wide range of application in respect both to the materials filled and the sizes in which it 40 is put up, and allowing for the variation in sizes of the same class of bottles that are usual in commerce.

To these ends the invention resides in a 45 rotary bottle filling machine possessing the novel features of construction and manner of operation substantially as hereinafter described and more particularly pointed out in the claims.

My invention, in a preferred mechanical 50 form, is illustrated in the accompanying drawings, wherein,—

Figure 1 is a central vertical sectional view through the complete machine; Fig. 2 is an enlarged top plan view of the station-

ary member of an air-valve mechanism controlling the flow of compressed air to and from the bottle lifts, the main upright shaft appearing in cross-section. Fig. 3 is an enlarged vertical sectional view through the air-valve mechanism controlling the flow of 55 air to and from the bottle lifts, and showing also the means for driving the rotary member of said air-valve mechanism; Fig. 4 is a horizontal sectional view through the main upright shaft and the rotary member of the 60 air-valve mechanism on the line 4—4 of Fig. 3; Fig. 5 is a similar view on the line 65 5—5 of Fig. 3; Fig. 6 is a detail side elevational view of the lower portion of the machine frame showing a source of compressed 70 air driven from the driving shaft; Fig. 7 is a cross-sectional view illustrating the means for driving the bottle-withdrawing mechanism from the main upright shaft of the machine; Fig. 8 is a longitudinal sectional 75 view on an enlarged scale of a bottle-charging valve mechanism; Fig. 9 is a view of the valve shown in Fig. 8 in a plane at right angles to the latter figure, certain parts appearing in elevation and others in vertical 80 section; and Fig. 10 is a cross-sectional view of the valve shown in Figs. 8 and 9, on the line 10—10 of the latter figures.

Referring to the drawings, 12 designates the circular base-plate on which is rigidly 85 mounted a stationary pedestal comprising a hollow circular base member 13 and a vertical cylindrical member 14 which is annularly cored to form a compressed air reservoir 15 and a central sleeve 16 that constitutes an extended bearing for the lower portion of the main upright shaft. 17 stepped centrally on the base-plate 12, preferably by means of anti-friction bearings indicated at 18. Resting on the upper end of 90 the main upright shaft 17 is a circular head in the form of a tank 19 adapted to be closed in an air-tight manner by a lid or cover 20 that may be secured thereto as by means of hinge-bolts 21 engaging forked 100 lugs 22 on the periphery of said cover. The upper portion of the shaft 17 has one or more longitudinal feathers 23, and beneath the latter a threaded portion 24. Secured to the under side of the tank 19 centrally 105 thereof is a depending sleeve 25, which surrounds the shaft 17 and has one or more grooves engaging the feather or feathers 23.

On the lower end of the sleeve 25 is rotatably secured a nut 26 internally threaded to engage the threaded portion 24 of the shaft, by rotating which nut the tank may be raised or lowered relatively to the upper end of the shaft 17 while still maintaining its driven relation to the latter.

Referring next to Figs. 1 and 3, 27 designates as an entirety a horizontally disposed plate that surrounds the shaft 17 and is secured in an air-tight manner to the upper end of the air reservoir casing 14 as by the bolts 28 and the interposed packing 29. This plate constitutes a stationary member of the air-valve mechanism that controls the flow of compressed air from the underlying reservoir to the several air lifts of the bottles hereinafter described. As shown in Figs. 3 and 5 said plate has a pair of arc-shaped cored passages 30 and 31 separated by vertical webs 32 and 33, the former being approximately 240 degrees in extent and the latter approximately 120 degrees in extent. To the passage 30 the compressed air in the underlying reservoir 15 is admitted through a vertical port 34, and from the passage 31 the exhaust air is discharged through a horizontal port 35. Through the upper wall of the passageway 30 is formed an arc-shaped port 36 coextensive longitudinally with the passageway itself; and through the upper wall of the passageway 31 is formed a similar arc-shaped port 37 coextensive longitudinally with said passageway. The plate 27 above the inlet and exhaust passageways last described is provided with a short vertical annular wall 27^a forming around the central upright shaft 17 an annular socket in which is seated a stationary rubber washer 38, superimposed on which is a fibrous washer 38^a of similar section, which washers are provided with arc-shaped ports 39 and 40, coextensive and registering with the underlying ports 36 and 37 and restrained by any suitable means against rotation. Seated on said washer is a revolving member of the air-valve mechanism, consisting of an annular block 41 loosely surrounding the shaft 17. Said block seats at its lower end on the washer 38^a, and is provided with a plurality of radially extending nipples 41^a (Fig. 4), through which nipples and the body of the block are formed a corresponding series of ducts 42 that open through the lower face of the block and are adapted to register with the passageways 39 and 40 of the washer 38, as clearly shown in Fig. 3. Surrounding and connected to the shaft 17 as by a set-screw 43 is a sleeve 44, between the lower end of which and the upper face of the revoluble air-valve member 41 is a coil spring 45, the office of which is to press the latter to its seat on the fibrous washer 38 in an air-tight manner. Depending from

the sleeve 44 are a series of lugs 44^a adapted to contact corresponding upstanding lugs 41^b on the rotary valve member 41, so as to drive the latter. Extending radially from the sleeve 44 are a series of arms 46 (Fig. 1), each carrying a cylindrical holder 46^a in which is secured a cylinder 47. The upper end of the cylinder is closed by a head or cap 48 provided with a port 48' and centrally apertured for the passage therethrough of a square piston rod 49 on the upper end of which is mounted a shoe 50 adapted to support a bottle 51. To the lower end of the cylinder is affixed a suitable cap 52 having an inwardly projecting portion 52^a that is provided with two air ducts. One of these, marked 53, communicates with the interior of the cylinder at its lower end, while the other, marked 54, communicates with the interior of the cylinder slightly above its lower end. The outer ends of said ports 53 and 54 communicate freely with an open pipe 55, the upper end of which is attached to one of the threaded nipples 41^a of the revoluble air-valve plate 41. To the lower end of the piston rod 49 is secured a piston or plunger head 56.

The base of the tank 19 has an annular series of openings 19^a formed therethrough, which are covered by the bottle-filling mechanism, next to be described. This mechanism, which is more fully shown in Figs. 8, 9 and 10, consists of the following. 57 designates a plate that may be secured to the base of the tank in a fluid-tight manner, as by means of screws or bolts 58. Depending from the plate 57 are a pair of parallel suspension rods 59 having heads or nuts 60 on their lower ends, on which is supported by apertured lateral ears 61 a valve block 105 casting 62. The plate 57 and valve block 62 are centrally apertured to slidably fit a tube 63 mounted therein and packed against leakage by suitable stuffing boxes 64 and 65. Between the glands of said stuffing boxes is interposed a compression coil spring 66; and fast on the tube 63 inside the spring 66 is a collar 67, constituting a lower abutment for an inner smaller coil spring 68, the upper end of which also abuts against the gland of the upper stuffing box. The upper end of the tube 63 is surmounted by a valve plate or disk 69, the lower operative face of which is provided with a fibrous or other packing ring 70, immediately beneath which the walls of the tube 63 are provided with one or more ports 71. The valve block 62 is cored to form a series of valve-controlled passages and ducts to control the passage of compressed air from the head or tank 19 into the bottles and the egress of such compressed air from the latter, as the bottles are filled, substantially as follows. 72 and 73 designate a pair of vertical passageways arranged on diametrically opposite sides of

the central tube 63, in the former of which is inserted a vein-valve 74 and in the latter a plug valve 75 having an operating handle 76. The lower ends of the passageways 72 and 73 both connect by horizontal ducts 77 and 78, respectively, with a central vertical annular opening 79 extending through the lower end of the valve block. Behind and between the vertical passageways 72 and 73 is cored a vertical cylindrical chamber 80 (Fig. 9), in which is a rod 81 having fast thereon a pair of separated piston heads 82 and 83. Said rod 81 extends above the valve block and is provided with a head or nut 84, between which and the upper end of the cylinder 80 is a coil spring 85 normally tending to maintain the pistons 82 and 83 in the elevated position shown in Fig. 9. The casing of the cylindrical chamber 80 has laterally projecting nozzles 86 and 87, the former of which has an axial duct 88 tapping the cylindrical chamber 80 substantially midway of its length, while the latter has an axial duct 89 tapping said chamber at its lower end. From the chamber 80 at a point slightly below the inlet of the duct 88 thereto extend ducts 90 and 91, the former leading to the upper end of the vein-valve 74, and the latter to the upper end of the vertical passage 73 above the plug valve 75, as plainly indicated in Figs. 8 and 10. The inlet nozzle 86 is connected by a flexible hose 92 (Fig. 1) with the interior of the tank 19 at or near its upper end; while the discharge nozzle 87 has attached thereto a similar flexible hose 93 that depends therefrom and debouches into an annular trough 94 secured to the central frame 14, substantially opposite the lower ends of the air cylinders.

The cover 20 of the tank head has a centrally disposed fluid inlet pipe 95 which may extend to within a short distance of the bottom of the tank. Where the machine is employed as a counter-pressure machine for the filling of fluid or liquors more or less impregnated with air or gas, and which consequently are liable to foam, I provide in the cover 20 a short tube 96 adapted to permit the discharge of air as the liquid enters up to a certain point, said tube being provided on its lower end with a valve seat 96^a; and in the tank I provide a hinged float 97 which carries a valve 98 adapted to close said seat on the rise of the fluid and thereby confine the body of air remaining in the tank above the liquid, and thus, by creating a pressure equal to the hydrostatic head of the incoming liquid, to thereby arrest the inflow of such liquid until the height in the tank is lowered by the filling of the bottles. Into this space air discharged from the bottles flows, and such excess is relieved automatically as the liquid falls, since the falling of the float retracts the valve from its seat,

thereby allowing a fresh flow of liquid to the tank until a like condition of balance is again reached.

A simple and convenient means of imparting rotary motion to the main upright shaft 70 17 and the various parts carried thereby consists, as herein shown, of a horizontal worm wheel 99 fast on the lower end of the shaft and housed within the hollow base 13, said worm wheel being driven by a 75 worm 100 on a drive-shaft 101 disposed substantially tangential to said worm wheel. The air maintained under pressure in the tubular reservoir of the machine for operating the bottle lifts may be drawn from any suitable or convenient source; but in order to make the machine complete and self-contained, I preferably provide an air-compressing device in intimate association with the machine and operated from the source 80 of power that drives the machine itself. For this purpose I have herein shown an air compressor cylinder 102 (Figs. 1 and 6) that discharges into the reservoir 15, the piston rod 103 of said cylinder being 90 driven through a pitman 104 from a gear 105 mounted on a counter-shaft 106 and driven by a pinion 107 fast on the drive-shaft 101.

Provision for discharging the filled bottles mechanically is afforded by means of a star wheel 108 that is mounted on the upper end of a vertical shaft 109 opposite and extending into the circular path traversed by the bottles in the rotation of the 100 machine, said shaft 109 being conveniently driven from the main upright shaft 17 by means of a sprocket 110 on the latter driving a link belt 111 which in turn actuates a sprocket 112 on said shaft 109. 105

The lower end of the valve block 62 has an externally threaded depending flange 62^a within which is secured an annular rubber gasket 113, confined in place by a ring 114 screwed onto the flange 62^a. The lower face of the gasket and the opening of the ring are beveled or concaved, as shown in Fig. 8, to form a suitable seat for air-tight engagement with the upper end of a bottle; and, in order to insure the entry of 115 the tubes 63 into the necks of the bottles as well as to accurately guide the latter into perfect registration with the valve seat, I preferably employ a bell 115 carried by a bracket 116 that is mounted to slide freely 120 on a vertical rod 117 passing through apertures in upper and lower lugs 116^a and 116^b of the bracket, said rod 117 being removably secured as by setscrews 118 and 119 in notched lugs 120 and 121 carried by the base 125 of the tank and the revolving bottle carrier 46, respectively. The upper contracted end of the bell 115 is axially apertured to slidely receive the depending filling tube 63, the bell sliding over said tube as it rises. 130

The opening in the upper end of the bell is of somewhat greater diameter than the upper end of the neck of the bottle, so that the latter in registering with the valve seat 5 passes entirely through the bell, engaging the latter by the sides of the neck.

The operation of the machine, briefly described, is as follows. Assuming that the air reservoir 15 is charged with compressed air, and the machine is otherwise in condition for operation, the liquid to be filled is allowed to flow into the tank and, raising the float 97 and closing the valve 98, compresses the air above its surface to a degree of pressure 10 equaling the hydrostatic head or pressure of the liquid at its source of supply. The pistons 82 and 83 of the valve mechanism being in the relative position shown in Fig. 9, the compressed air in the tank is held against escape so long as the bottle-charging valve mechanism is in its lowermost position shown therein. The shoes of the air lifts being supplied with bottles, and the machine being started in operation, 15 as soon as each of the ducts 42 of the revolving air valves passes into registration with the passageway 39 that communicates with the passage 30 of the stationary member of the air valve, the compressed air from the reservoir 15 flows instantly through the tube 55 and the lower duct 63 to the under side of piston 56, causing the latter to rise and carrying with it the superposed bottle 51. As soon as the piston has passed the auxiliary duct 54 an additional supply of compressed air enters the cylinder casing the piston and its load to rise more rapidly. As soon as the neck of the bottle engages the bell 115 it is centered by the latter (if not 20 previously in true axial alignment with the valve tube 63), whereupon the bell is carried upwardly on its sliding support, the lower end of the tube 63 entering the mouth of the bottle. As soon as the upper end of 25 the bottle contacts the elastic gasket 113 of the filling valve mechanism, the valve block 62 begins to rise on top of the bottle being guided by the suspension rods 59 on which it slides. As soon as the valve casing has 30 risen sufficiently to lower the piston 82 to a point beneath the lateral ducts 90 and 91, the inlet passage 88 is placed in communication with said ducts whereupon the compressed air above the fluid in the head or 35 tank passes freely and quickly through the duct 90, vein-valve 74, duct 77 and annular passage 79 to the interior of the bottle, the compressed air to a more limited extent also finding its way through the ducts 91, 73 and 40 78 to the annular passage 79 and the interior of the bottle, the extent of this latter flow depending upon the extent to which the plug valve 75 is set to throttle and limit the flow. In this manner equilibrium of pressure 45 in the head and bottle is quickly estab-

lished before the flow of liquid begins. On the still further upward rise of the valve block 62, the gland of the lower packing box 65 strikes the collar 67 which is fast on the tube 63, and raises the valve 69, thus allowing flow of the liquid to be charged into the bottle through the opening or openings 71 and the interior of the tube. By reason of the described equilibrium of pressure in the tank and bottle, this flow occurs solely by gravity, which, together with the condensed condition of the air surrounding said liquid, eliminates the bubbling and foaming that would otherwise occur, or reduces it to a minimum. The use of the plug valve 75 is to regulate and restrict the speed of the air discharge from the bottles on the liquid commencing to flow, and by impeding the fall or flow of the liquid to still further prevent foaming, providing, in fact, a mechanical means of retarding the flow in addition to the physical means provided by the establishment of equal pressures in the tank-head and bottles. By the time the bottle is charged with liquid, the revolving member 40 of the air-valve mechanism has carried the air conduit passage to the bottle-lifting cylinder over the web 32 or 33 (according to the direction of rotation), and brought it into communication with the exhaust 90 through the passageway 31. Thereupon the bottle-lift begins to descend, forcing the air out of the cylinder to the atmosphere, the descent occurring more slowly in its final movement after the piston has passed the lateral inlet duct 54. With the descent of the bottle and the valve block 62 (forced downwardly by the spring 66) the pistons 83 and 82 rise, until, just before the bottle breaks its connection with the seat 113, the piston 82 uncovers the mouth of the duct 91, thus permitting such air or gas pressure as remains in the neck of the bottle to blow out by a quick movement through the passages 79, 78, 73, 91, cylinder 80, and exhaust passage 89, into the drip tube 93, thus sniffling the bottle. So much of the fluid as is thus blown off in the final operation is directed by the drip tube 93 into the stationary trough 94, from which latter it may be discharged as desired; such residue in the case of valuable liquors being saved and returned to the original source of supply. Each bottle, while undergoing the above described operation, travels around approximately 110 three-quarters of a single revolution of the machine, the filled bottles being withdrawn from the shoes of the air lifts one by one in succession by the star wheel 108, their places being supplied with empty bottles by the attendant in charge.

Where the machine is used in the filling of heavy liquids, such as catsup, or other liquids not charged with air or gas and hence not liable to bubble and foam during 115

the filling operation, the means hereinabove described for maintaining an equilibrium of pressure in the tank and bottles may be dispensed with or rendered inactive by allowing the interior of the tank above the liquid to remain in constant communication with the atmosphere or with any feed tank attached to it.

The described pneumatic means for raising the bottles into engagement with the filling valve mechanism and maintaining them in such engagement during the filling operation possesses numerous advantages over the mechanical means heretofore employed in such machines, as follows. The action is more elastic and hence produces less shock and jar upon the bottles and is therefore less liable to break or injure the latter. The air lift mechanism permits a considerable variation in the size or height of the bottles without requiring readjustment or resetting of the parts of the machine conformable thereto. The double inlet for the compressed air at the lower end of the air lift cylinder is of importance, as it provides for a slow initial rising movement of the bottle, permitting a gradual centering of the bottle, affording ample time to the operator in loading the machine and disposing of the filled bottles, and avoiding concussions or shocks in starting the upward movement of the bottle. The greater part of the downward movement of the piston is comparatively rapid because the air will escape from the cylinder through the two ports 53 and 54, but after the piston passes the port 54 an air cushion will be formed at the bottom of the cylinder by reason of the restricted outlet through the single port 53, and this air cushion avoids shocks or jars which would have a tendency to make the beer foam. Aside from the capability of the machine in handling bottles of a given size presenting variations in height due to irregularities or imperfections of manufacture by reason of the air lift feature and the vertical adjustability afforded by the nut 26, the machine is also readily adaptable to the filling of various sizes of bottles, such as quarts, pints and splits. To adapt a machine to the filling of pints and splits the ring 114 is withdrawn and replaced by a sleeve 114^a of suitable length, itself terminating in a rubber-lined mouth 113^a (similar to the gasket 113) adapted to receive the head of the smaller bottle, as indicated in Fig. 9. This amounts in effect to a longitudinal adjustment of the filling valve block to accommodate various sizes or heights of bottles to be filled. The presence of the compressed air reservoir within the frame of the machine itself conduces both to economy of space and to the maintenance of a substantially steady and uniform pressure of the air supply to the bottle lifts. The trough 94 which

receives the drip resulting from the shifting of the bottles is also of importance, as it prevents waste of the valuable residue or overflow, besides dispensing with the necessity on the part of the operators of wearing liquid-proof coats or aprons, since the rapid and continual shifting of the bottles produces a sloppy condition in the absence of some means, such as that herein described, for confining such discharge.

While I have illustrated and described in considerable detail the bottle filling valve mechanism connected to the tank head, yet, inasmuch as said valve mechanism may be substituted by other valve mechanism operating in substantially the same way and effecting the same results, I do not claim the novel features of said valve mechanism in the present application, but have made them the subject matter of a companion application filed on the 12th day of April, 1905, Serial No. 255,153.

It is evident that the machine as hereinabove described and shown in the drawings might be considerably modified and varied in respect to details of construction and the relative disposition of the parts without departing from the principle or sacrificing any of the benefits of the invention. Hence, I do not limit the invention to such details of construction and arrangement except to the extent indicated in specific claims.

I claim:

1. In a bottle filling machine, the combination of a rotatable upright shaft, a tank carried by said shaft, a series of bottle filling valves connected to said tank, a series of fluid pressure bottle lifts carried by said shaft, and a valve controlling the fluid supply to said bottle lifts and operated during the rotation of said shaft.

2. In a bottle filling machine, the combination of a rotatable upright shaft, a tank carried by said shaft, a series of bottle filling valves connected to said tank, a series of fluid pressure bottle lifts carried by said shaft, and a valve connected to and operated by said shaft for controlling the fluid supply to said bottle lifts.

3. In a bottle filling machine, the combination of a rotatable upright shaft, a tank carried by said shaft, a series of bottle filling valves connected to said tank, a series of fluid pressure bottle lifts carried by said shaft, and a valve connected to and operated by said shaft for controlling the fluid supply to and from said bottle lifts.

4. In a bottle filling machine, the combination of a base, a rotatable upright shaft mounted on the base, a tank carried by said shaft, a series of bottle filling valves connected to said tank, a series of fluid pressure bottle lifts carried by said shaft, a fluid pressure reservoir in the base, and an automatically operated valve for controlling the

flow of fluid from said reservoir to the bottle lifts.

5. In a bottle filling machine, the combination of a rotatable upright shaft, a tank 5 carried by said shaft, a series of bottle filling valves connected to said tank, a series of fluid pressure bottle lifts carried by said shaft, a fluid pressure reservoir, and a two part valve, for controlling the flow of fluid 10 from said reservoir to the bottle lifts, one part of said valve being made to rotate with the shaft.

6. In a bottle filling machine, the combination of a rotatable upright shaft, a tank 15 carried by said shaft, a series of bottle filling valves connected to said tank, a series of fluid pressure bottle lifts carried by said shaft, a fluid pressure reservoir, and a two part valve, for controlling the flow of fluid 20 from said reservoir to the bottle lifts, one part of said valve being made to rotate with the shaft and the other part being made fast to the reservoir.

7. In a bottle filling machine, the combination of a base, a rotatable upright shaft 25 mounted in the base, a tank carried by said shaft, a series of bottle filling valves connected to said tank, a series of fluid pressure bottle lifts carried by said shaft, and a two 30 part automatically operated valve for controlling the flow of fluid from the supply to said bottle lifts, one of said parts being stationary and the other being made to rotate with the shaft.

35 8. In a bottle filling machine, the combination of a base, a rotatable upright shaft mounted on the base, a tank carried by said shaft, a series of bottle filling valves connected to said tank, a series of fluid pressure 40 bottle lifts carried by said shaft, a fluid controlling valve comprising a fixed member communicating with the fluid supply and a movable member, and a fluid pipe connecting each bottle lift and said movable member.

45 9. In a bottle filling machine, the combination of a base, a rotatable upright shaft mounted on the base, a tank carried by said shaft, a series of bottle filling valves connected to said tank, a series of fluid pressure bottle lifts carried by said shaft, and a fluid controlling valve comprising a stationary member having an inlet passage communicating with the fluid supply and a movable 50 member having a series of ports each connected with a bottle lift and adapted to be moved into registration with said inlet passage.

55 10. In a bottle filling machine, the combination of a base, a rotatable upright shaft mounted on the base, a tank carried by said shaft, a series of bottle filling valves connected to said tank, a series of fluid pressure bottle lifts carried by said shaft, and a 60 fluid controlling valve comprising a station-

ary member having a fluid inlet and a fluid outlet passage, the former communicating with the fluid supply, and a movable member having a series of ports each communicating with a bottle lift and adapted to be moved into registration with said passages.

11. In a bottle filling machine, the combination of a base, a rotatable upright shaft mounted on said base, a tank carried by said shaft, a series of bottle filling valves connected to said tank, a series of fluid pressure bottle lifts carried by said shaft, and a fluid controlling valve comprising a stationary member mounted on the base and having fluid inlet and exhaust passages, the former 75 communicating with the fluid supply, and a movable member made to rotate with said shaft and having a series of ports each communicating with a bottle lift and adapted to be moved into registration with said passages.

12. In a bottle filling machine, the combination of a base, a rotatable upright shaft mounted on the base, a tank carried by said shaft, a series of bottle filling valves connected to said tank, a series of fluid pressure bottle lifts carried by said shaft, and a fluid controlling valve comprising a stationary member having a fluid inlet passage connected with the fluid supply, and a rotatable member carried by the shaft and provided with a series of ports each communicating with a bottle lift and adapted to be moved into registration with said inlet passage, and yielding means for holding said movable member seated against the stationary member.

13. In a bottle filling machine, the combination of a base, a rotatable upright shaft mounted on said base, a tank carried by said shaft, a series of bottle filling valves connected to said tank, a series of fluid pressure bottle lifts carried by said shaft, and a main fluid controlling valve encircling said shaft and comprising a stationary member having a fluid inlet passage and a movable member made to rotate with the shaft and having a series of ports each communicating with a bottle lift and adapted to be moved into registration with said passage, and a spring bearing down on the movable member to hold it against its seat on the stationary member.

14. In a bottle-filling machine, the combination with a frame, a compressed air reservoir, an upright shaft journaled in said frame, a tank carried by said shaft, and a series of bottle-filling valves carried by said tank, of a bottle-supporting frame keyed to said shaft and carrying a series of bottle-raising and lowering cylinders, and an air-valve mechanism communicating with said reservoir, said cylinders, and the atmosphere; said valve mechanism admitting compressed air to said cylinders during a

portion of the travel of the latter around said shaft and discharging air therefrom during the remainder of said travel.

15. In a bottle-filling machine, the combination with a pedestal frame hollowed to provide an annular compressed air reservoir, an upright shaft journaled in and axially of said pedestal, a tank carried by said shaft, and a series of bottle-filling valves carried by said tank, of a bottle-supporting frame keyed to said shaft and carrying a series of bottle-raising and lowering cylinders, a stationary annular valve member secured to said pedestal and having 10 inlet and discharge ports communicating with said reservoir and the atmosphere, respectively, a revoluble valve member mounted on said stationary valve member and having a series of ducts communicating successively with the inlet and discharge ports 15 of said stationary member, and tubes connecting said ducts with said cylinders.

16. In a bottle filling machine, the combination of a rotatable tank, a plurality of 20 bottle filling valves carried by the tank, and a plurality of fluid pressure bottle lifting mechanisms rotatable with the tank and located opposite the filling valves, each of said 25 lifting mechanisms comprising a cylinder, a piston working in the cylinder, and means for automatically regulating the supply of 30 actuating fluid to said cylinder to impart to the piston a slow initial upward movement and thereafter a comparatively rapid 35 upward movement.

17. In a bottle filling machine, the combination of a rotatable tank, a plurality of bottle filling valves carried by the tank, and a plurality of fluid pressure bottle lifting 40 mechanisms rotatable with the tank and located opposite the filling valves, each of said 45 lifting mechanisms comprising a cylinder having two ports therein arranged one above the other, a piston working in the cylinder, and means for supplying fluid under 50 pressure to said cylinder through said ports whereby the piston has imparted thereto a comparatively slow movement while the fluid is entering the cylinder 55 through one port and thereafter a more rapid movement when the fluid enters the cylinder through both ports.

18. In a bottle filling machine, the combination of a rotatable tank, a plurality of 55 bottle filling valves carried by the tank, and a plurality of fluid pressure bottle lifting mechanisms rotatable with the tank and located opposite the filling valves, each of said 60 lifting mechanisms comprising a cylinder, a piston working in the cylinder, and means for automatically regulating the exhaust of actuating fluid from said cylinder to impart to the piston a rapid movement for the greater part of its downward stroke 65 and a comparatively slow cushioned move-

ment as the piston approaches the limit of its downward stroke.

19. In a bottle filling machine, the combination of a rotatable tank, a plurality of bottle filling valves carried by the tank, and a plurality of fluid pressure bottle lifting mechanisms rotatable with the tank and located opposite the filling valves, each of said lifting mechanisms comprising a cylinder having two ports therein arranged 70 one above the other, and a piston working in the cylinder and adapted to have a rapid downward movement while the fluid is escaping through both ports and a retarded and cushioned movement after the piston 75 passes the upper port.

20. In a bottle filling machine, the combination of a rotatable tank, a plurality of bottle filling valves carried by the tank, and a plurality of fluid pressure bottle lifting 80 mechanisms rotatable with the tank and located opposite the filling valves, each of said lifting mechanisms comprising a cylinder, a piston working in the cylinder, and means for automatically regulating the supply of 85 fluid to the cylinder and the exhaust of fluid therefrom to impart to the piston a comparatively slow movement at the beginning of its upward stroke and a slow cushioned movement at the end of its downward stroke. 90

21. In a bottle filling machine, the combination of a rotatable tank, a plurality of bottle filling valves carried by the tank and a plurality of fluid pressure bottle lifting 95 mechanisms rotatable with the tank and located opposite the filling valves, each of said lifting mechanisms comprising a cylinder having two ports therein arranged one above the other, a piston working in the cylinder, and means for supplying fluid under 100 pressure to one of said ports to impart to the piston a slow initial upward movement and then to both ports to accelerate the movement of the piston and for exhausting said fluid from the cylinder first through 105 both ports and then through one port to impart to the piston a comparatively rapid downward movement through the greater part of its stroke while both ports are open and then retarding the movement of the piston 110 near the limit of its downward stroke when the fluid is being exhausted through one port only.

22. In a bottle filling machine, the combination of a rotatable tank, a plurality of bottle filling valves connected to the tank, and a plurality of fluid pressure bottle lifting mechanisms rotatable with the tank and located opposite the filling valves, each of said lifting mechanisms comprising a cylinder having two ports arranged one above the other, a fluid pressure supply, means for conducting the fluid to and from both ports of said cylinder, and an automatically operated valve for controlling the supply of fluid 120 125 130

to and the exhaust of fluid from said cylinder.

23. In a bottle filling machine, the combination of a rotatable tank, a plurality of 5 bottle filling valves carried by the tank, and a plurality of fluid pressure bottle lifting mechanisms rotatable with the tank and located opposite the filling valves, each of 10 said lifting mechanisms comprising a cylinder having a port entering one end thereof and an auxiliary port communicating with the cylinder laterally near said end, means for supplying fluid under pressure to and exhausting it from said ports, a piston, a piston-rod, and a bottle-rest actuated by 15 said piston-rod.

24. In a bottle filling machine, the combination of a rotatable tank, a plurality of bottle filling valves carried by the tank, and 20 a plurality of fluid pressure bottle lifting mechanisms rotatable with the tank and located opposite the filling valves, each of 25 said lifting mechanisms comprising a cylinder having a double-ported cylinder-head, one port leading into the end of the cylinder and the other into the side of the cylinder near said end, means for supplying a fluid 30 under pressure to and exhausting it from said ports, a piston, a piston-rod, and a bottle-rest actuated by said piston-rod.

25. In a bottle filling machine, the combination of a rotatable tank, a plurality of bottle filling valves carried by the tank, and a plurality of fluid pressure bottle lifting 35 mechanisms rotatable with the tank and located opposite the filling valves, each of 40 said lifting mechanisms comprising a cylinder having its lower end closed by a double-ported cylinder-head, one port whereof leads into the end of said cylinder and the other 45 into its side near said end, means for supplying a motive fluid to and exhausting it from said ports, a piston, a piston-rod, and a bottle-rest carried on the upper end of said piston-rod.

26. In a bottle-filling machine of the char-

acter described, the combination with a hollow supporting frame containing a compressed air reservoir, of a vertical shaft journaled in said frame, a tank-head carried by said shaft, bottle-filling valves carried by said tank-head, a series of pneumatic bottle-lifts carried by said shaft and supplied with motive fluid from said compressed air reservoir, a driving shaft geared to said vertical shaft, and an air compressor geared to said driving shaft and supplying compressed air to said air reservoir.

27. In a bottle filling machine, the combination of a rotatable upright shaft, a tank mounted on said shaft, a series of filling valves connected to said tank, a filling tube depending from each valve, a series of bottle lifts carried by said shaft below the filling valves, and successively operated and independent means separate from the filling tubes for centering each bottle as it rises into registering engagement with its filling valve and comprising a vertical guide adjacent to each filling tube, a bracket slidably mounted on said guide, and a bell carried by said bracket to receive the mouth of the bottle.

28. In a bottle filling machine, the combination of a rotatable upright shaft, a tank mounted on said shaft, a series of filling valves connected to said tank, a filling tube depending from each valve, a frame keyed to said shaft, a series of successively operated bottle lifts carried by said frame, and independent means for centering each bottle as it rises into registering engagement with its filling valve and comprising a vertical guide secured at its ends to said tank and frame behind each filling tube, a bracket slidably mounted on said guide, and a bell carried by said bracket.

CHARLES L. BASTIAN.
